UNITED STATES PATENT OFFICE.

**WILLIAM C. CLARK AND EDWARD C. CLARK, OF WELLSTON, AND LOUIS WEHRHEIM,
OF ST. LOUIS, MISSOURI.**

DESIGN FOR A PLANT-PROTECTOR.

59,885.

Specification for Design.

Patented Dec. 6, 1921.

Application filed February 25, 1921. Serial No. 447,887. Term of patent 7 years.

To all whom it may concern:

Be it known that we, **WILLIAM C. CLARK, EDWARD C. CLARK, and LOUIS WEHRHEIM**, all citizens of the United States, the first two of us residing at Wellston, in the county of St. Louis and State of Missouri, and the third at St. Louis, in the county of St. Louis and State of Missouri, have invented a new, original, and ornamental Design for Plant-Protectors, of which the following is a specification, reference being had to the accompanying drawing, forming a part thereof.

The figure is a perspective view of a plant protector showing our new design.

We claim:

The ornamental design for a plant protector, substantially as shown.

In testimony whereof, we have hereunto subscribed our names.

**WILLIAM C. CLARK.
EDWARD C. CLARK.
LOUIS WEHRHEIM.**
